UNITED STATES PATENT OFFICE.

PETER L. PETERSON, OF MANTI, UTAH.

SHOE-HEEL DEVICE.

1,171,749.

Specification of Letters Patent. Patented Feb. 15, 1916.

Application filed April 25, 1914. Serial No. 834,445.

To all whom it may concern:

Be it known that I, PETER L. PETERSON, a citizen of the United States, residing at Manti, in the county of Sanpete and State 5 of Utah, have invented certain new and useful Improvements in Shoe-Heel Devices, of which the following is a specification.

The object of my invention is to provide a device to be used upon a shoe to prevent

10 a rubber or overshoe when in use sliding up and down on the heel of the shoe or becoming accidentally displaced therefrom.

A further object is to provide a device of the character described comprising two 15 mating members, a socket member to be attached permanently to the shoe, and a hook member to be attached to the rubber or overshoe at a point to be engaged in the socket when the overshoe is in place and to hold securely therein until manually released.

With other objects in view, which will be referred to, my invention consists in the 20 peculiar combination and novel arrangement of parts, such as will be hereinafter more fully described in connection with the accompanying drawing and more particularly pointed out in the appended claims.

In the drawing:—Figure 1 is a view in 25 perspective of the rear portion of a shoe with an overshoe in place thereon and showing my device applied. Fig. 2 is a view in elevation of the socket member which is attached to the shoe. Fig. 3 is a view in top 30 plan of the disclosure in Fig. 2. Fig. 4 is a view in elevation of the hook member which is attached to the overshoe. Fig. 5 is a view in top plan of the member disclosed in Fig. 4.

35 The device comprises the two mating members 1 and 2, the socket member 1 being adapted to be secured to the shoe on the heel of the upper and the hook member constructed to be fastened to the inner part of 40 the heel portion of the overshoe so that when the overshoe is in place the two members meet, the hook of the one being received in the socket of the other.

45 The member 1 is provided in its body portion with a plurality of openings 3 and is curved transversely as better shown in Fig. 3, so that it will fit the shape of the upper of the shoe adjacent the heel. Staples or rivets 4 are received through the

openings 3 and through the upper of the 55 shoe and are clenched down against the side of the shoe to hold the member 1 secured in place thereon. At the upper edge the plate from which the member 1 is formed is bent outwardly to form a socket 5 which 60 socket projects only slightly from the leather of the shoe.

The member 2 as better shown in Fig. 5 is bent transversely to conform very closely to the shape of the member 1 and its body 65 portion has the openings 6 provided to receive rivets or other fastening means 7 which are passed through the upper of the overshoe and through this plate of the member 2 where they are clenched to hold 70 the member secured within the overshoe. The upper edge of the member 2 is bent over to form a hook 8 which is made to project only slightly from the face of the plate and is of a dimension to be received 75 in the socket 5 of the member 1.

In use, it is preferable that the member 2 be secured to the inner side of the heel of the overshoe at a point probably half an 80 inch from the upper edge thereof, and the member 1 is secured to the upper of the shoe on the heel in such a position that when the overshoe is placed upon the shoe and is brought into its proper fit thereon, the hook 8 engages in the socket 5 and the two 85 members are held mated together against accidental displacement. When it is desired to remove the overshoe from the shoe, the overshoe is grasped at the upper edge and the hook 8 disengaged from the socket 90 5 after which the overshoe may be readily removed.

From the foregoing, it will be seen that I have provided a device of the character described, inexpensive to manufacture and 95 readily applied by anyone to a shoe and overshoe, and one which when in operative relation prevents the overshoe working up and down over the heel of the shoe and absolutely precludes possibility of the overshoe becoming accidentally removed from the shoe.

100 While I have herein shown and described one specific form of my invention, it will be understood that slight changes might be 105 made in the form and arrangement of the several parts without departing from the spirit and scope of my invention, and hence

I do not wish to be limited thereto except for such limitations as the claims may import.

I claim:—

- 5 1. A device of the character described, comprising a plate curved to conform to the shape of and adapted to be secured to the counter of an inner shoe at the rear end thereof, and provided with a socket at its
- 10 upper edge, and a second plate adapted to be secured to the inside of an overshoe and curved to conform closely to the shape of the first plate and provided with a hook of a size to enter said socket, said plates being
- 15 adapted to be arranged and connected to the inner shoe and overshoe in such relation that as the overshoe is fitted in place on the inner shoe, the hook will engage with the socket to hold the overshoe against removal.
- 20 2. A device to secure an overshoe on an inner shoe comprising a single sheet metal plate curved to conform to the shape of and

adapted to be secured to the counter of an inner shoe at the rear portion thereof, said 25 plate bent outwardly at the upper edge to provide a socket, and a second member adapted to be secured to the inside of an overshoe comprising a single sheet metal plate curved to conform closely to the shape 30 of the first plate and provided at its upper edge with a tongue bent over to form a hook to be received in the socket of said first plate, said plates being adapted to be arranged and connected to the inner shoe 35 and overshoe in such relation that as the overshoe is fitted in place on the inner shoe, the hook will engage with the socket to hold the overshoe against removal.

In testimony whereof I affix my signature in presence of two witnesses.

PETER L. PETERSON.
